UNITED STATES PATENT OFFICE.

WILLIAM H. McINTYRE, OF TOLEDO, OHIO, ASSIGNOR OF ONE-FOURTH TO FRANK M. SALA AND FOUR-TWENTIETHS TO GEORGE W. CORE.

PISTON-VALVE.

1,222,115.

Specification of Letters Patent. Patented Apr. 10, 1917.

Application filed January 10, 1914, Serial No. 811,387. Renewed June 2, 1916. Serial No. 101,391.

To all whom it may concern:

Be it known that I, WILLIAM H. McINTYRE, a citizen of the United States, residing at Toledo, county of Lucas, and State of Ohio, have invented new and useful Improvements in Piston-Valves, of which the following is a specification.

My invention relates to an improvement in explosive gas engines, and has to do more particularly with the valve mechanism for controlling the intake and exhaust, it being adapted to any of the present types of explosive gas engines. By it I am enabled to do away with much of the usual paraphernalia which goes with explosive engines, such as springs, lifts, cams, sleeves, and other accessories which easily get out of working order and decrease the life and efficiency of a machine of this sort.

The desideratum is to provide a motor that will be noiseless; and another important feature of the invention resides in confining the entire explosive charge directly over the end of the piston.

In the accompanying drawings:

Figure 1 is a transverse vertical sectional view,

Fig. 2 is a sectional view taken at right angles to Fig. 1,

Fig. 3 is a top plan view of one unit, and

Fig. 4 is an end elevation of the lower end of the engine with the face-plate removed in order to show the gearing.

A, represents the bed of the engine, which may be made of angle-iron, and to which the crank-case 1 is bolted as at 2, 2.

Erected upon each crank-case is a set of three cylinders, namely the main explosion cylinder 3 in the center, and the valve-cylinders 4, and 5, on either side thereof, the three preferably being cast together and held on the crank-case by bolts 6, 6. The main piston 7 is fitted to the bore of cylinder 3, and from its wrist-pin 8 the connecting rod 9 extends to the crank 10 on the main drive-shaft 11, which latter is journaled in boxes 12, 12, in the crank-case.

The explosion-chamber 13 is formed at the outer end of the main piston 7, and spark-plug 14 is tapped thereto for igniting the charge.

Cast on the sides of the main cylinder are the valve-cylinders 4 and 5 with the usual water-jackets 15, 15, therebetween. Fitted to the bores of the cylinders 4 and 5 are

the cylindrical reciprocating-valves 16 and 17. These are controlled by connecting rods 18, 18, extending from wrist-pins 19, 19 to the cranks 20, 20' on the shafts 21, 21', the latter receiving their motion through 60 sprocket-chains 22, 22, driven from the sprocket-wheel 23 to sprocket wheels 24, 24, which are timed one to two.

Through the valves 16 and 17, the tapering ports 25 and 26 are formed respectively, 65 the former communicating at its larger end with the exhaust 27 through the port 28, and the latter, namely the intake 29, with the larger end of port 26, and the smaller end with the port 30.

The valves 16 and 17 are packed at either end with compression-rings 31 to prevent the escape of compression.

A balance-wheel 32 is keyed to the drive-shaft 11 in the usual manner.

On the intake-side, the port 26 through which the carburetor charge is admitted can be held open for the entire length of the suction-stroke, the engine illustrated being a four-cycle engine. Also the exhaust port 80 can be held open the entire length of the exhaust-stroke.

In operation the intake-port 30 starts to open on the last part of the outward stroke of the valve 17, the port 26 remaining open 85 while the crank 20' is traveling across the outer part of its circle, holding the port 30 open while the main piston 7 makes the entire travel of the suction-stroke, thus bringing parts 30, 26, and intake 29 into alignment forming an intake directly to the explosion-chamber 13, which alignment is maintained during the entire suction-stroke. The port 28 on the exhaust side is opened on the outward stroke of the exhaust-valve 16, 90 and is held open by the shaft 21 taking advantage of the travel of the crank-shaft 20 across the outer circle, ports 27, 25 and 28 being held open during the entire exhaust stroke of the main piston 7, bringing ports 100 27, 25 and 28 into alignment, forming a direct outlet for the exhaust, which alignment is maintained during the entire exhaust stroke.

As shown in Fig. 1, intake ports 30, 26 105 and 29 are open and held open during the entire quarter outward turn of crank 21'; while the driving or piston-shaft 11 is making a rapid downward entire suction stroke. In other words, the timing feature of this en- 110

- gine is a means of taking advantage of the travel across the top or outer circle of shaft 21', while the main crank is making the downward stroke, which has much more movement on the side travel than it has on the top and bottom; that is to say the main crank-shaft 11 has a drop of five inches, while the side-shaft is varying only seventeenth of an inch in traveling across its outer upward circle turn.
- In this way, a perfect valve action is provided as the intake ports are open during the entire length of the suction stroke, and the exhaust ports during the entire length of the exhaust stroke, and opened mechanically, it gives an absolute positive valve action and cleans all burnt gases from the cylinder; and when the ports 28 and 30 are closed, the charge of pure gas is compressed by the piston 7 into the compression chamber 13 at the outer end thereof, thus giving the motor the advantage of the entire explosion and concentration of power and gas at the outer end of the piston.
- In this manner I am enabled to do away with cams, springs, tappets, valve-cages, and cam-shafts, and by so doing provide a practically noiseless motor which dispenses with all parts that are most liable to wear out, lose power and cause trouble.
- At the same time, by my invention I pro-

vide a motor, which, while not liable to get out of order, is, nevertheless, capable of easy repair by any mechanic.

I claim:—

In an explosive gas engine, the combination of an explosion cylinder, and cylindrical valve-chambers having communicating ports, intake and exhaust ports in alignment with said communicating ports, a piston in the explosion cylinder, cylindrical valves fitted to the valve-chambers, said valves having ports extending directly therethrough, a main crank-shaft, valve-cranks, said cranks geared to said main crank-shaft in a ratio of two to one, connecting-rods extending from the cranks to the piston and valves, and the cranks so arranged with respect to one another that the port of each valve is in registry with the corresponding ports when its crank is passing dead center, and when the main crank-shaft is off dead center.

In witness whereof I have hereunto signed my name in the presence of the attesting witnesses hereto, this 3rd day of December, A. D. 1913.

W. H. McINTYRE.

Attesting witnesses:

F. M. SALA,
N. J. LYNCH.
